UNITED STATES PATENT OFFICE.

OTTO J. GROEHN, OF DETROIT, MICHIGAN, ASSIGNOR TO BRISCOE MANUFACTURING COMPANY, OF DETROIT, MICHIGAN, A CORPORATION OF MICHIGAN.

METHOD OF FORMING SHEET METAL.

1,167,556.

Specification of Letters Patent. Patented Jan. 11, 1916.

Application filed June 11, 1914. Serial No. 844,447.

To all whom it may concern:

Be it known that I, OTTO J. GROEHN, a citizen of the United States of America, residing at Detroit, in the county of Wayne 5 and State of Michigan, have invented certain new and useful Improvements in Methods of Forming Sheet Metal, of which the following is a specification, reference being had therein to the accompanying 10 drawings.

The invention relates to the manufacture of articles from sheet metal having warped or double curved surfaces, which cannot be formed from a flat blank without flowing 15 the metal, and the present application is filed as an improvement on a pending application Serial No. 786,014, filed August 21, 1913.

More specifically, the invention relates to 20 the manufacture of fenders for the wheels of automobiles and other vehicles, and it is the object to obtain a simple and inexpensive process by which the metal may be fashioned to the desired form without the 25 use of large dies and expensive machinery.

In the present state of the art automobile fenders are commonly formed from sheet metal which is curved in one plane only and may therefore be readily formed from 30 a flat blank without drawing or flowing of the metal. There is, however, a demand for fenders which are concavo-convex in cross section, as well as being curved longitudinally in conformity to the wheel, but such 35 constructions cannot be made by the process commonly used. It is possible to produce such form by suitable drawing dies, but this requires heavy and expensive machinery, and on account of the large number 40 of sizes and variations and frequent change in shape, such a process is not a commercial success. The present invention overcomes these difficulties by the formation of the desired shapes by a rolling or progressive 45 treatment of the blank; and further, by a method of holding the blank during the rolling or forming action so as to prevent buckling or deformation of any part thereof.

The invention further comprises the supplementing of the progressive forming step by die operations for completing the article in certain portions thereof.

In the drawings: Figure 1 is a longitudinal section showing the manner of rolling

and forming sheet metal; Fig. 2 is a cross section through a machine in which the metal is rolled; Fig. 3 is a section showing the manner of die-fashioning portions of the blank; Fig. 4 is a view similar to Fig. 2, showing a modified construction; Fig. 5 60 is a cross section through the blank before the following operation; and Fig. 6 is a plan view of the blank.

In forming of articles from flat sheet metal blanks so as to produce warped or 65 transversely-curved surfaces, it is essential to draw or elongate certain portions of the blank, or to contract or upset other portions. With relatively light gage sheet metal it is difficult to avoid the wrinkling of the 70 portions of the blank which are subjected to compression stresses, and also to prevent distorting of the blank by the drawing stresses. To take a specific instance, a wheel 75 fender which is curved longitudinally, substantially concentric with the wheel and transversely to have a convex cross section, the longitudinal center of the blank must be drawn or expanded while the marginal portions will be subjected to compression 80 stresses. Furthermore, the drawing of the central portion, which should be in a longitudinal direction, will react transversely of the blank to produce a distortion thereof.

To avoid the result just described, I provide in my improved process, means for holding the marginal portions of the blank in such a manner that they are prevented on the one hand from wrinkling by any upsetting stresses, and on the other hand are held 90 from displacement laterally of the blank under any drawing stress applied to the central portion thereof. Various specific means may be employed for obtaining this result, but preferably that shown in Figs. 1 to 3, in 95 which A is the blank and B B' are hooked flanges bent from the opposite edge portions. These flanges B B' are formed primarily for obtaining a retaining engagement with the guides during the drawing operation, 100 but they also perform a function in the fashioned article as a means of attachment to the depending vertical flanges of the fender. The flat blank being first formed with these reversely-bent edges, as shown in Fig. 3, is 105 then passed through a drawing machine comprising essentially complementary concave and convex rolls C and D. During the pe-

riod of engagement with these rolls, as well as for a certain distance before and after engagement, the hooks B and B' are engaged with marginal retaining guides E and E'.
5 These are so fashioned as to receive the hooks of the blank and to hold the adjacent portion between parallel contacting surfaces. This will prevent the drawing of the blank inward and will also prevent the
10 buckling of the margin portions under the influence of the bulging portion of the roll. The portion of each of the guides E and E' beyond the rolls extends at an angle to the original plane and is preferably curved to
15 correspond to the longitudinal contour to be imparted to the product. It is not, however, necessary that the contour of the guide should exactly conform to the contour of the finished product, as the angle at the point
20 of longitudinal bending is the controlling factor, and thus with the same guide variations in the curve may be produced by an angular adjustment with respect to the original plane of the blank.
25 To facilitate the feeding of the blanks between the rolls C and D, a central tongue F is formed at the entrance end, which may be more readily deflected downward into engagement with the convex portion of the
30 roll, and when thus engaged will draw the whole blank into engagement. The opposite end of the blank may be correspondingly recessed at G, to permit the tongue of a following blank to engage therewith, and the
35 following blank will thus propel the advance blank until disengaged from the rolls and guides. Where the bulging contour is comparatively flat, it is preferably held from distortion by a shoe H arranged adjacent to
40 the delivery side of the rolls C and D. To complete the article, it is necessary to form the end portions thereof, and this is preferably accomplished by pressing between dies, such as I and I', shown in Fig. 3. In
45 place of forming the blank with the hooked flanges at opposite edges, the blank may be attached to marginal guide strips J and J', as shown in Fig. 4, and these strips may be held from inward movement by abutting

against the ends of the rolls or by any other suitable means.

What I claim as my invention is:—

1. The method of fashioning sheet metal blanks to warped or transversely-curved forms, comprising the progressive bulging 55 of the central portion of the blank to stretch the metal longitudinally and transversely, and the holding of the marginal portions of the blank from inward movement during this operation to prevent buckling.

2. The method of fashioning sheet metal blanks to warped or transversely-curved forms, comprising the progressive bulging 65 of the central portion of a sheet metal strip, and the holding from inward movement and the guiding of the marginal portions of said strip to prevent buckling and to determine the longitudinal contour.

3. The method of fashioning sheet metal blanks to warped or transversely-curved 70 forms, comprising the formation of marginal flanges longitudinally of the flat sheet metal strip, the bending of said strip to bulge the central portion thereof, and the holding of the marginal portions during 75 said bending movement to prevent drawing toward each other and to hold the same from buckling.

4. The method of fashioning sheet metal blanks to warped or transversely-curved 80 forms, comprising the forming of a sheet metal strip with hooked flanges upon opposite edges thereof, feeding said strip longitudinally and simultaneously bulging the central portion thereof, the bending of the 85 strip longitudinally during its feeding movement to conform to a predetermined curve, and the guiding of the hooked flanges at the margin of said strip to prevent movement toward each other and to hold the same from 90 buckling.

In testimony whereof I affix my signature in presence of two witnesses.

OTTO J. GROEHN.
